US00D974551S

(12) **United States Design Patent** (10) Patent No.: **US D974,551 S**
(45) Date of Patent: ** Jan. 3, 2023

(54) CONNECTOR ASSEMBLY AND CONNECTOR	4,443,028 A	4/1984	Hayes
(71) Applicant: Fisher & Paykel Healthcare Limited , Auckland (NZ)	4,446,869 A	5/1984	Knodel
(72) Inventors: Rachel Nicole Mosen , Auckland (NZ); Christopher Peter Hutchinson , Aliso Viejo, CA (US); Emeric Henri Michel Belleux , Auckland (NZ); Hugo Max Treherne James , Auckland (NZ)	4,584,997 A	4/1986	Delong
	4,589,684 A	5/1986	Nowacki et al.
	4,601,495 A	7/1986	Webb
	4,661,110 A	4/1987	Fortier et al.
	4,676,241 A	6/1987	Webb et al.
	4,773,448 A	9/1988	Francis
	D300,271 S	3/1989	Rudolph et al.
	D300,272 S	3/1989	Rudolph et al.
	D302,040 S	7/1989	Lambert et al.
	5,040,527 A	8/1991	Larson et al.
	5,064,226 A	11/1991	Klas
	D328,033 S	7/1992	DiGuiseppe
	5,158,569 A	10/1992	Strickland et al.
	5,335,656 A	8/1994	Bowe et al.
	D362,718 S	9/1995	Deily et al.
	D363,541 S	10/1995	Cottone, Sr. et al.
	5,529,284 A	6/1996	Berger et al.
	5,584,997 A	12/1996	Yagihashi et al.
	5,725,258 A	3/1998	Kujawski
	5,735,271 A	4/1998	Lorenzen et al.
	D395,502 S *	6/1998	Deily D24/129
	5,901,705 A	5/1999	Leagre
	D424,687 S	5/2000	Hoenig et al.
	6,099,519 A	8/2000	Olsen
	D431,634 S	10/2000	Mantz
	D439,326 S	3/2001	Hecker et al.
	D449,107 S	10/2001	Madsen
	6,439,234 B1	8/2002	Curti et al.
	6,484,724 B1	11/2002	Sloan
	D468,015 S	12/2002	Horppu
	D472,316 S	3/2003	Douglas et al.
	D472,630 S	4/2003	Douglas et al.
	6,561,549 B1	5/2003	Moris et al.
	6,581,974 B1	6/2003	Ragner et al.
	6,893,055 B2	5/2005	Thomas et al.
	6,915,705 B1	7/2005	Truitt
	6,932,390 B1	8/2005	Gretz
	6,953,354 B2	10/2005	Edirisuriya
	7,007,694 B2	3/2006	Aylsworth et al.
	D522,360 S	6/2006	Caserta
	7,201,167 B2	4/2007	Fink et al.
	D543,620 S	5/2007	Chu et al.
	D547,657 S	7/2007	Tacchella
	D551,340 S	9/2007	Wood et al.
	7,263,994 B2	9/2007	Gradon et al.
	7,267,121 B2	9/2007	Ivri
	D553,005 S	10/2007	Py
	7,290,541 B2	11/2007	Ivri et al.
	D556,899 S	12/2007	Veliss et al.
	7,306,121 B2	12/2007	Ophardt
	7,311,752 B2	12/2007	Tepper

CLAIM

We claim, the ornamental design for a conduit connector, as shown and described.

DESCRIPTION

FIG. 1 front, right side perspective view of a first embodiment of a conduit connector embodying our new design. FIG. 2 is a rear, left side perspective view thereof.

FIG. 3 is a top view thereof.

FIG. 4 is a bottom view thereof.

FIG. 5 is a front view thereof.

FIG. 6 is a rear view thereof.

FIG. 7 is a left side view thereof.

FIG. 8 is a right side view thereof.

FIG. 9 is a sectioned view through the line 9-9 shown in FIG. 5.

FIG. 10 is a sectioned view through the line 10-10 shown in FIG. 5.

FIG. 11 front, right side perspective view of a second embodiment of a conduit connector embodying our new design.

FIG. 12 is a rear, left side perspective view thereof.

FIG. 13 is a top view thereof.

FIG. 14 is a bottom view thereof.

FIG. 15 is a front view thereof.

FIG. 16 is a rear view thereof.

FIG. 17 is a left side view thereof.

FIG. 18 is a right side view thereof.

FIG. 19 is a sectioned view through the line 19-19 shown in FIG. 15.

FIG. 20 is a sectioned view through the line 20-20 shown in FIG. 15.

FIG. 21 front, right side perspective view of a third embodiment of a conduit connector embodying our new design.

FIG. 22 is a rear, left side perspective view thereof.

FIG. 23 is a top view thereof.

FIG. 24 is a bottom view thereof.

FIG. 25 is a front view thereof.

FIG. 26 is a rear view thereof.

FIG. 27 is a left side view thereof.

FIG. 28 is right side view thereof.

FIG. 29 is a sectioned view through the line 29-29 shown in FIG. 25; and,

FIG. 30 is a sectioned view through the line 30-30 shown in FIG. 25.

The references to "left," "right," "front," "rear," "top," and "bottom" in the figure descriptions are not meant to require certain in-use orientation; the connector assemblies and connectors according to the claimed design may be used in any orientation.

Broken lines are used to illustrate features of the conduit connector which form no part of the claimed design.
